APPARATUS FOR MERCERIZING CLOTH

Maurice S. Dayan, New York, N. Y.

Application May 14, 1949, Serial No. 93,390

8 Claims. (Cl. 26—51)

1

My invention is an improved process and apparatus for treating cloth preliminary to dyeing; and particularly for mercerizing the fabric.

The improvement relates chiefly to the treatment of tubular cloth that is generally produced by knitting; and an important object is to provide a process and apparatus by which long pieces of tubular cloth can be mercerized by a continuous operation and at greatly reduced expense.

Another object is to provide a process and apparatus for flattening and stretching tubular cloth both longitudinally and transversely, in the first step, and maintaining it at the proper tension during contact with the mercerizing agent and the washing medium.

Other objects and advantages of my invention are fully described hereinafter; and the distinguishing features are pointed out in the claims. I do not wish to be restricted to the exact details of structure or mode of proceeding disclosed herein; for changes may be made without deviation from the principle of the invention and without omission or basic alteration of any of the essential steps or parts.

On the drawings:

Figure 1 is a top view of the apparatus employed for my invention and the manner in which the process is performed.

Figure 2 is a side view of what appears in Figure 1; and

Figures 3, 4, 5 and 6 show details.

The numeral 1 indicates a piece of tubular cloth produced by knitting or otherwise. This cloth when laid out flat is in separate layers 2 and 3, integrally united along the lateral edges. The cloth is stretched both longitudinally and transversely in the performance of the process; and is first passed between a pair of rolls 4, placed one above the other; and bearing against the upper layer 2 and lower layer 3. Before entering the rolls 4 a spreader member 5 is inserted into the end of the cloth to distend and flatten it. This spreader has the form of an open frame and rests upon the top of a table or other suitable support 6. In the final stage the cloth arrives at another pair of rolls 7. Before reaching the rolls 7, the cloth is passed through a tank 8 containing a solution of caustic soda, and then through another vessel 9 which contains only wash water. Between the receptacles 8 and 9 the cloth is exposed to the air for the required interval. The rolls 4 and 7, known as "nip rolls," stretch the cloth lengthwise, and the member 5 stretches it in width before it enters the tank 8. The rolls 4 and 7 are made out of any suitable

2

material, and are so mounted that the pressure thereof against the cloth 1 can be adjusted as may be necessary. They impart to the cloth required longitudinal tension as it moves through the vessels 8 and 9, and of course have the required size and weight.

The spreader frame 5 is made of tubular metal, with parallel sides 11, and a rear end 12. The front end 13, which is pushed first into the cloth, 10 is shorter, and may either be rounded, or joined to the sides 12 by short diagonal portions 14 as shown in Figure 3. The parts of the frame are too thick to pass between the rolls 4. Hence the frame remains stationary with the cloth 1 as the latter is drawn between the rolls 4. More than one spreader can be used inside the cloth before it enters the rolls 4, but in such a case, each should be a little wider than the one ahead of it, to stretch the cloth progressively as it passes 20 into the rolls 4.

After leaving the rolls 4, the cloth 1 is subjected to action of the long spreader frame 10, the latter being of greater breadth than any spreader in front of the rolls 4. The spreader 10 25 extends over both tanks 8 and 9, which have a space between them to expose the cloth to the air. When the successive portions of the cloth enter the tank 8 it has been stretched both lengthwise and crosswise to the full extent necessary.

Over the spreader 10 the cloth is pulled by the rolls 7 into the soda tank 8. In its passage through this tank it is kept distended by the long spreader 10 which has a horizontally disposed end of suitable size shown at 15 overlapping the intake end of the tank 8, and a long curved part 16 that is bent down into the tank 8. This spreader also has a long curved section 17 bent down into the tank 9 and a straight horizontal intermediate member or section 18 between the two tanks. The distance between the soda tank 8 and the water bath 9 is enough to expose the cloth to the air for the time needed. Beyond the vessel 9 the frame 10 has a horizontally disposed end 19 overlapping the outlet end of this vessel 9. 45 The sides of the spreader 10 have cross braces 20 between them to maintain uniform width throughout.

The cross bars 20 are attached to the sides 21 and 22 with smooth junctions, so that no corners or projections are present to catch and tear the cloth. The bends are rounded and the dips in the frame where the parts 16 and 17 curve downward into the tanks 8 and 9 are at a gradual incline to assure smooth easy motion of the cloth.

The long spreader 10 may be equipped with

anti-friction elements in the form of wheels 23 mounted on journals in recesses 25 at suitable intervals along the outer faces of the sides 21 and 22. The cross bars can be relatively thick like bolsters and rounded at their opposite ends as shown at 24 in Figure 5.

The process gives a thoroughly mercerizing action and can be rapidly and continuously performed. The cost of mercerizing with my invention is greatly reduced, without loss or reduction in efficiency, and the results are all that can be desired. After leaving the water bath tank, the cloth can be wound again into "rope," and be made ready for dyeing and such further treatment as the cloth may need to finish it; including further washing and scouring as required. The water in the tank 9 sets the cloth after mercerizing.

The cross rods 20 or 24 and the anti-friction wheels 23 can be as numerous and set as close together as may be necessary. The wheels 23 can be mounted in slots 25 in the sides 21 and project from the slots. These slots are horizontal, so that the rollers project laterally from the sides 21 and 22. See Figure 6. They can also be mounted on the upper or lower surfaces of the sides.

When the cloth leaves the tank 8 it can be squeezed between a pair of soft rolls 26 adjacent the outlet end of the tank to expel excess soda solution. The rolls 7 are preferably supported just above the outlet end of the tank 9, within the edge thereof, so that excess water is squeezed out in the same way and drops into the tank. The rolls 4 and 7 are operated at suitable rates of speed to stretch the cloth lengthwise between them.

Having described my invention, what I believe to be new is:

1. Apparatus for mercerizing tubular cloth comprising a vessel for a mercerizing agent and a vessel for a washing medium, a pair of rolls for engaging the cloth adjacent the intake end of the first vessel, a pair of rolls adjacent the outlet end of the other vessel, and a spreader frame extending through both vessels.

2. Apparatus for mercerizing tubular cloth comprising a vessel for a mercerizing agent and a vessel for a washing medium, a pair of rolls for engaging the cloth adjacent the intake end of the first vessel, a pair of rolls adjacent the outlet end of the other vessel, and a spreader frame extending through both vessels, said frame carrying anti-friction elements disposed along the length thereof.

3. Apparatus for mercerizing tubular cloth comprising a vessel for a mercerizing agent and a vessel for a washing medium, a stretcher member projecting beyond the intake end of the first vessel and the outlet end of the second vessel, said member having curved sections extending smoothly downward into both vessels between the ends of each, and a pair of rolls adjacent each end of said member.

4. Apparatus for mercerizing tubular cloth comprising a vessel for a mercerizing agent and a vessel for a washing medium, a stretcher member projecting beyond the intake end of the first vessel and the outlet end of the second vessel, said

member having curved sections extending smoothly downward into both vessels between the ends of each, and a pair of rolls adjacent each end of said member, said member having anti-friction elements disposed at points along the length thereof.

5. Apparatus for mercerizing tubular cloth comprising a vessel for a mercerizing agent and a vessel for a washing medium, a stretcher member projecting beyond the intake end of the first vessel and the outlet end of the second vessel, said member having curved sections extending smoothly downward into both vessels between the ends of each, and a pair of rolls adjacent each end of said member, said member having anti-friction elements disposed in slots at points along the length thereof.

10 6. Apparatus for mercerizing tubular cloth comprising a vessel for a mercerizing agent and a vessel for a washing medium, a stretcher member projecting beyond the intake end of the first vessel and the outlet end of the second vessel, said member having curved sections extending smoothly downward into both vessels between the ends of each, and a pair of rolls adjacent each end of said member, said member having anti-friction elements disposed in slots at points along the length thereof.

15 7. An apparatus for mercerizing tubular cloth comprising a vessel for a mercerizing agent and a vessel for a washing medium, rolls for engaging the cloth adjacent the intake end of the first vessel, rolls adjacent the outlet end of the other vessel, spreading means in the first vessel for the cloth, spreading means in the second vessel for the cloth, and a spreading section extending between the spreading means in the two vessels.

20 8. An apparatus for mercerizing tubular cloth comprising a vessel for a mercerizing agent and a vessel for a washing medium, rolls for engaging the cloth adjacent the intake end of the first vessel, rolls adjacent the outlet end of the other vessel, spreading means in the first vessel for the cloth, spreading means in the second vessel for the cloth, and a spreading section extending beyond the surfaces thereof.

25 9. An apparatus for mercerizing tubular cloth comprising a vessel for a mercerizing agent and a vessel for a washing medium, rolls for engaging the cloth adjacent the intake end of the first vessel, rolls adjacent the outlet end of the other vessel, spreading means in the first vessel for the cloth, spreading means in the second vessel for the cloth, and a spreading section extending between the spreading means in the two vessels.

30 10. An apparatus for mercerizing tubular cloth comprising a vessel for a mercerizing agent and a vessel for a washing medium, rolls for engaging the cloth adjacent the intake end of the first vessel, rolls adjacent the outlet end of the other vessel, spreading means in the first vessel for the cloth, spreading means in the second vessel for the cloth, and a spreading section extending beyond the surfaces thereof.

35 11. An apparatus for mercerizing tubular cloth comprising a vessel for a mercerizing agent and a vessel for a washing medium, rolls for engaging the cloth adjacent the intake end of the first vessel, rolls adjacent the outlet end of the other vessel, spreading means in the first vessel for the cloth, spreading means in the second vessel for the cloth, and a spreading section extending between the spreading means in the two vessels.

40 12. An apparatus for mercerizing tubular cloth comprising a vessel for a mercerizing agent and a vessel for a washing medium, rolls for engaging the cloth adjacent the intake end of the first vessel, rolls adjacent the outlet end of the other vessel, spreading means in the first vessel for the cloth, spreading means in the second vessel for the cloth, and a spreading section extending between the spreading means in the two vessels.

45 13. An apparatus for mercerizing tubular cloth comprising a vessel for a mercerizing agent and a vessel for a washing medium, rolls for engaging the cloth adjacent the intake end of the first vessel, rolls adjacent the outlet end of the other vessel, spreading means in the first vessel for the cloth, spreading means in the second vessel for the cloth, and a spreading section extending between the spreading means in the two vessels.

50 14. An apparatus for mercerizing tubular cloth comprising a vessel for a mercerizing agent and a vessel for a washing medium, rolls for engaging the cloth adjacent the intake end of the first vessel, rolls adjacent the outlet end of the other vessel, spreading means in the first vessel for the cloth, spreading means in the second vessel for the cloth, and a spreading section extending between the spreading means in the two vessels.
